WILLIAM J. GAGNON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRICAL ROSETTE.

1,039,670.

Specification of Letters Patent. Patented Sept. 24, 1912.

Application filed June 25, 1908. Serial No. 440,323.

To all whom it may concern:

Be it known that I, WILLIAM J. GAGNON, a citizen of the United States of America, residing in Bridgeport, in the county of Fairfield, in the State of Connecticut, have invented certain new and useful Improvements in Electrical Rosettes, of which the following is a specification.

The object of my invention is to so constrict an electrical rosette as to relieve from the strain of the weight of the suspended lamp or the like, the connection between the bared ends of the wires and the binding screws or other means for securing them to the terminal plates in the rosette. This object I attain in the manner which I will now describe.

In the accompanying drawings Figure 1 is a view of a rosette with the cap in section 20 on the line 1—1, Fig. 2; Fig. 2 is an inner face view of the cap; Fig. 3 is a perspective view of the cap without the wires or fuses; Fig. 4 is an inner face view of a fuseless type of rosette.

25 In Fig. 1, B is the base, which may be of any suitable construction, but preferably of porcelain. C is the cap, which is also preferably of porcelain and is detachably secured to the cap by any well known or suitable means, such as the notched plates a , a' , Figs. 2 and 3, to take over screws on the base in the well known way. In the fuseless rosette shown in Fig. 4, I have indicated spring latches a^2 on the terminal plates A^2 30 of the cap to engage suitable hooks or plates on the base. In the construction shown in Figs. 1, 2 and 3, the terminal plates A, A ^{1} , to which the ends of the suspension cords are to be connected by binding screws 5, 5, 40 are secured to the cap separate from the attaching plates a , a' , but electrically connected to the latter by fuse wires f , f' .

45 The cords D, D ^{1} which pass through the usual central hole c in the cap, have their bared ends secured to the terminal plates A, A ^{1} or A ^{2} , A ^{2} by suitable binding screws 5, 5. Between these terminal plates and the central aperture I form on the inner face of the cap abutments or vertical studs, 50 around which the covered portions of the wires may be bent or coiled to take the strain of the weight of the suspended lamp and cords from the connection of the cords with the terminal plates. I have shown such abutments at E, of such a character as

to impart to each wire at least a complete U-shaped bend in passing from the terminal plate to the outlet hole. I prefer to provide an abutment E ^{1} (or E ^{2} , Fig. 4) so as to make the bend in each wire a U-shape in 60 two directions, reversed, or in other words, an S-shape, as shown. These abutments are also preferably so formed with relation to each other and adjacent parts of the cap as to produce grooves of a width not more than 65 the diameter of the covered wires, so as to add the frictional contact of the wires with the walls of the grooves to the frictional hold of the bent but covered portions of the wires with the corners of the abutments. 70 The abutments are formed in the porcelain in the molding operation and the grooves are open so that the wires can be readily laid within and around the abutments, either after or before connecting up their 75 bared ends to the terminal plates A, A ^{1} , or A ^{2} , A ^{2} . These abutments must be of such size and bear such relation to the terminal plates that the corners of the abutments will be engaged by the covered or insulated portions of the wires and not by the bared wires. Otherwise there would be liability of 80 breaking of the wire strands.

I claim as my invention—

1. An electrical rosette, having a cap carrying terminals and having a central aperture with two strain-relieving abutments formed on the inner face of the cap for each wire between the terminal and the aperture. 85

2. An electrical rosette, having a cap provided with wire terminals and a central aperture and having formed on its inner face strain-relieving abutments forming open grooves to receive and hold the wires in S-bends. 90

3. In an article of the character described, the combination, with a body portion provided with a central opening, two wire terminals and two vertical studs, of an electric lamp-cord extending through said central opening, and having its inner end portion coiled around said studs and connected to said wire terminals. 100

4. In an article of the character described, the combination, with a body portion provided with a central opening, two wire terminals and two vertical studs, of an electric lamp-cord extending through said central opening and having its inner end portion coiled around said studs and connected to 105 110

said wire terminals, and means for holding the coils in position upon said studs.

5. In an article of the character described, the combination, with a body portion comprising a base and a removable cap portion, each provided with a pair of wire terminals, and means for connecting the wire terminals upon the base portion with the wire terminal, upon the cap portion when said 10 cap portion is secured to the base, of a central opening in said cap portion, two vertical studs formed upon said cap portion and an electric lamp-cord extending through said central opening and having its inner 15 end portion coiled around said studs and connected to said wire terminals.

6. In an article of the character described, the combination, with a base portion provided with two wire terminals, of a cap por-

tion provided with a central opening, two 20 wire terminals, an electric lamp-cord extending through said central opening and having its inner end coiled around projections formed in said cap portion and connected to the wire terminals in said cap portion, and 25 a pair of fuse wires extending from the wire terminals in said cap portion through suitable grooves formed in the body of said cap portion to a pair of contact plates adapted to engage and disengage the wire terminals. 30

In testimony whereof I have signed my name to this specification, in the presence of two subscribing witnesses.

WILLIAM J. GAGNON.
